MACHINE FOR THE CONTINUOUS CASTING
OF METAL RODS

Ilario Properzi, Milan, Italy

Application December 6, 1950, Serial No. 199,387

Claims priority, application Italy January 21, 1950

3 Claims. (Cl. 22—57.4)

1

The present invention relates to an improved apparatus for continuously casting metal rods.

Machines for the continuous casting of indeterminate lengths of metal rods are known. In some of such machines the liquid metal is poured into a channel provided on the periphery of a rotatable casting wheel and closed by a flexible ribbon which engages the periphery of the wheel for movement with said wheel.

As disclosed in my co-pending patent application, Serial Number 78,372, filed February 25, 1949, the ribbon may be in the form of an endless band looped over the casting wheel and an idler pulley having an axis of rotation parallel to and spaced from the axis of rotation of the casting wheel.

Although these machines represent a notable improvement in the manufacture of metal rods and wires, in particular from non-ferrous metals, they must be carefully operated due to the difficulty of adjusting the outflow of the liquid metal from the nozzle of the crucible into said casting channel. As a matter of fact, if the quantity of outflowing metal is excessive, a turbulence occurs, which causes stoppage of the casting operation, whilst scarce outflow of metal causes defective shaping not in compliance with industrial requirements.

The requirement for adjusting the delivery of liquid metal appears even more desirable as it may be necessary for the operator to be able to vary the speed of the casting wheel in accordance with the quality of the metal employed and with the shape of the cross-section of the rod to be obtained, and it would consequently be desirable to vary also the quantity of delivery of the fluid stream from the crucible.

It is therefore an object of the invention to provide an improved continuous metal casting machine of the type having a rotatable casting wheel or drum with a peripheral casting groove to cooperate with an endless band looped about the periphery of the casting wheel and an adjacent idler wheel whose axis of rotation is parallel to but spaced from the casting wheel axis of rotation, the improvement providing for the adjustment of the delivery of molten metal to the casting groove during operation of the machine and the adjustment of the speed of rotation of the casting wheel during operation of the machine.

A feature of the present invention as provided in a continuous casting machine of the kind hereinbefore described is the arrangement wherein the idler pulley and the pouring crucible are

2

mounted on a pivotal supporting member, which can be rotated and fixed in the desired position about the axis of the casting wheel. When rotating pivotal support, the crucible assumes different inclinations and with equal quantities of metal contained therein, the fluid head varies with respect to the delivery cross-section of the pouring spout and, therefore, the delivered quantity of the fluid vein flowing out of it varies.

10 The machine according to the invention may be further provided with a continuous speed changer, with which it is possible to vary the speed of rotation of the casting wheel in accordance with the different requirements of different metals being cast, and to compensate for changes effected by varying the inclination of the crucible.

Further objects, features and the attending advantages of the invention will be apparent with reference to the following specification and drawing in which:

Fig. 1 is a side elevation partly in section of a machine according to the invention for the continuous casting of metal rods;

Fig. 2 is a front view of the machine; and

Fig. 3 is a fragmentary detail in section of the pouring crucible.

The machine comprises essentially a casting wheel or drum 1 rotatable about the axle 2 and rotated by means of a chain 3 connected to the gear reducer 4 which in turn is driven by the motor 5 through a continuous speed changer 6 of any suitable known form.

30 The wheel or drum 1 is provided with an annular channel 7 on the periphery thereof which is adapted to be closed by a flexible ribbon 8. The ribbon is looped over the wheel 1 and the idler pulley 9 in such a manner as to form an endless band.

35 The casting wheel 1 is cooled in a known manner by means of water circulating in the interspace 10 of the wheel 1 and arriving and discharging through the hollow spokes of said wheel. The numeral 11 designates the crucible from which the molten metal is poured tangentially into the channel 7 by way of the spout 12. According to the present invention, the crucible 11 and the idler pulley 9 are mounted on a common pivotal support 13, which can rotate about the axle 2 of the casting wheel 1.

40 The pivotal support 13 is rotated by operating the crank handle 14 carried on the support 13 and rotatable with a toothed pinion engaging a rack 15 secured to the base frame 16 of the machine. Suitable locking means (not shown) may be provided to secure support 13 in a desired position.

As shown in Fig. 1 of the drawing, the pulley 9 is rotatably supported at the end of a plunger 17 slidable in a cylindrical cavity of the support 13 and pushed outward by the band tensioning compression spring 18.

In the position shown in Fig. 1, the liquid head under which there is the outlet cross-section of the spout 12, is represented by the height difference h . As shown in Fig. 3 the crucible 11 may be moved to a different position upon rotation of the crank handle 14 by a certain amount in the direction of the arrow of Fig. 1.

Under such conditions, the inclination of the crucible 11 increases and thus also the head H increases, under which there is the outlet cross-section of the spout.

The continuous speed changer 6 provides for possible differences of pouring adjustments as well as to vary the speed of the casting wheel or drum 1 in compliance with particular working requirements of the particular metal to be cast.

Various modifications may be made within the spirit of the invention and the scope of the appended claims.

Having now particularly described and ascertained the nature of my said invention and in what manner the same is to be performed, I declare that what I claim is:

1. In apparatus for the continuous casting of molten metal which has a wheel having an annular channel rotatably supported on a base structure and which also has a movable flexible ribbon enclosing an arcuate portion of the channel, the combination with said wheel and ribbon of supporting means rotatably mounted on the base structure coaxially with the axis of rotation of the wheel and extending radially beyond the periphery of the wheel, a pulley rotatably mounted on said supporting means and supporting the movable ribbon taut over the aforesaid arcuate portion of the channel in a looped configuration, crucible means mounted on said supporting means in a position so that at least a portion of said crucible extends within the loop of the ribbon, said crucible means having a spout directed into the aforesaid channel, and adjustable means for rotating said supporting means about the axis of rotation of the wheel to move said pulley and crucible means relative to the periphery of the wheel through an arc and control the rate of flow from said crucible means.

2. In apparatus for the continuous casting of molten metal which has a wheel having an annular channel rotatably supported on a base structure and which also has a movable flexible ribbon enclosing an arcuate portion of the channel, the combination with said wheel and ribbon of a support member rotatably mounted on the base structure coaxially with the axis of rotation of the wheel and extending radially beyond the periphery of the wheel, a pulley rotatably mounted on said support member and supporting the

movable ribbon taut over the aforesaid arcuate portion of the channel in a looped configuration, crucible means mounted on said support member in a position so that at least a portion of said crucible extends within the loop of the ribbon, said crucible means having a spout directed into the aforesaid channel, a rack mounted on the base structure, and control means including a pinion rotatably mounted on said support member and engaging said rack for rotating said support member about the axis of rotation of the wheel to move said pulley and crucible means relative to the periphery of the wheel through an arc and control the rate of flow from said crucible means.

3. In apparatus for the continuous casting of molten metal which has a wheel having an annular channel rotatably supported on a base structure and which also has a movable flexible ribbon enclosing an arcuate portion of the channel, the combination with said wheel and ribbon of supporting means rotatably mounted on the base structure coaxially with the axis of rotation of the wheel and extending diagonally upward beyond the periphery of the wheel, a pulley rotatably mounted on said supporting means and supporting the movable ribbon taut over the aforesaid arcuate portion of the channel in a looped configuration, crucible means mounted on said supporting means in a position so that at least a portion of said crucible extends within the loop of the ribbon, said crucible means having a pouring spout extending downwardly from the bottom thereof into the aforesaid channel and said crucible being shaped so that the head of any fluid therein with respect to the tip of said spout varies as the pivotal position of said crucible about the axis of rotation of the wheel is altered, and adjustable means for rotating said supporting means about the axis of rotation of the wheel to move said pulley and crucible means relative to the periphery of the wheel through an arc and control the flow from said pouring spout.

ILARIO PROPERZI.
